UNITED STATES PATENT OFFICE.

CHARLES FREDRICK BETTMANN AND JOHN ZAPP, OF NEW ALBANY,
INDIANA.

WIRE-SUPPORT.

SPECIFICATION forming part of Letters Patent No. 770,999, dated September 27, 1904.

Application filed July 8, 1903. Serial No. 164,222. (No model.)

To all whom it may concern:

Be it known that we, CHARLES FREDRICK BETTMANN and JOHN ZAPP, citizens of the United States, residing at New Albany, in the 5 county of Floyd and State of Indiana, have invented a new and useful Wire-Support, of which the following is a specification.

The present invention relates to devices for supporting electrical conductors, such as telephone, telegraph, and electric wires; and the 10 object is to provide an extremely simple article of this character that will constitute an efficient support for the conductors without the necessity of tying the same thereto. Said 15 articles, moreover, constitute clutches which will automatically secure the wire should the same break between adjacent poles or supports, thus preventing its falling to the ground or the street and endangering the lives of 20 passers-by.

Two embodiments of the invention are illustrated in the accompanying drawings.

Figure 1 is a side elevation of the preferred form of support, showing the same applied to 25 the crosstree of a pole. Fig. 2 is a vertical longitudinal sectional view through the same. Fig. 3 is an end elevation of the head. Fig. 4 is a detail perspective view of the upper portion of the support. Fig. 5 is a vertical 30 sectional view, on an enlarged scale, through a slightly-modified form of construction.

Similar reference-numerals indicate corresponding parts in all the figures of the drawings.

Referring to the embodiment illustrated in the first four figures, an insulator 10 is employed, which may be formed of glass, porcelain, rubber, or other suitable material, said insulator being constructed to be inserted 35 in an opening 11, formed in the usual crosstree 12 of a pole, though the device may be used in connection with other supports, as will be apparent. This insulator 10 has an enlarged boss 13 at its upper end, the upper 40 surface of said boss being rounded. The insulator, furthermore, is provided with a longitudinally-disposed bore 14, in which is revolvably mounted the lower portion of a supporting-stem 15. This stem is provided with

an intermediate rounded cap 16, that rests 50 upon and conforms to the shape of the upper face of the boss 13. The stem is secured against displacement by a suitable key 17, passed through its lower end, which end projects below the lower end of the insulator. It 55 will be observed that the length of the key 17 is greater than the diameter of the insulator, and thus bears against the under face of the crosstree, consequently securing the entire structure in said tree. The upper end of the 60 stem 15 has an offset neck 18, carrying a wire-engaging head. This head comprises an upright shank 19, secured between its ends to the end of the neck and having oppositely-extending beaks 20 attached at its ends, said 65 beaks being located at an inclination to the shank 19 and having their free terminals overlapped, but spaced slightly apart, as shown, to form a contracted entrance-throat 21. As a result of this particular arrangement a wire- 70 receiving seat 22 is formed that tapers toward its lower end. The stem is secured in the crosstree of a pole, as clearly shown in Figs. 1 and 2, and is thus freely revoluble. In stringing the wire it is only necessary to 75 pass the same through the contracted entrance-throat 21 and stretch it, keeping the same out of the lower end of the seat. After being stretched the wire is allowed to drop into said contracted end and will thus be supported without being tied to the article. Should the wire break between two of the 80 supports, however, the head, being offset from the axis of rotation of the stem, will turn slightly and the wire will be clutched tightly 85 in the seat. Thus the ends will not slide through the supports and fall to the ground. Decided advantages therefore are obtained 90 by the particular arrangement of the elements—namely, the freely-revoluble spindle and the offset head with its wire-receiving seat. Moreover, under ordinary conditions the wire cannot become detached, as it is out of alignment with the throat 21, through which it is passed.

A slightly-modified form of construction is illustrated in Fig. 5, wherein a portion of the article is shown, the parts not illustrated

bearing the same relation as those described. The stem is designated by the reference-
numeral 15^a and has a cap 16^a thereon that corresponds to the shape of the insulator.
5 Instead of a key for holding the spindle in place, the lower end of said spindle is threaded, and a holding-nut 17^a is screwed thereon. The stem, cap, and portions of the nut may be coated, as shown at 23, with suitable insulation, though this is not entirely necessary.
10

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages
15 of the invention.
20

Having thus described our invention, what we claim as new, and desire to secure by Letters Patent, is—

1. In a device of the class described, the
25 combination with an insulator-supporting device, of a supporting -stem journaled and freely rotatable in the supporting device, means for preventing the longitudinal movement of the stem in either direction in the
30 supporting device, and an offset head carried by the free end of the stem and rotatable therewith, said head having a wire-receiving seat that is offset from the axis of rotation of the stem.
35 2. In a device of the class described, the combination with a supporting-sleeve having an upright opening therethrough, of an up-

right supporting-stem passing through the opening and freely rotatable in the sleeve, means carried by the stem and engaging the 40 upper and lower ends of the sleeve for preventing the disengagement of said stem from the sleeve, and an offset head carried by the free end of the stem and rotatable therewith, said head having an inclosed wire-receiving 45 seat, that is offset from the axis of rotation of the stem.

3. In a device of the class described, a stem, and a head carried by the stem, said head comprising a shank and oppositely-extending 50 overlapping and outwardly-projecting beaks carried by the shank, said beaks being spaced from an intermediate portion of one side of the shank and located at an inclination thereto, forming an inclosed tapering wire-receiving 55 seat.

4. In a device of the class described, the combination with an insulator, of a stem journaled in the insulator and having a cap covering the upper end thereof, said stem being 60 also provided with an offset neck, and a head comprising an upright shank connected between its ends to the neck and having oppositely-extending overlapped beaks forming a wire-receiving seat.
65

In testimony that we claim the foregoing as our own we have hereto affixed our signatures in the presence of two witnesses.

CHARLES FREDRICK BETTMANN.
JOHN ZAPP.
